ANCHOR WITH RELEASABLE PIVOTED FLUKES

Lincoln H. Millen, Modesto, Calif.

Application January 29, 1947, Serial No. 725,130

1 Claim. (Cl. 114—208)

1

This invention relates to anchor construction, the primary object of the invention being to provide means for releasing the flukes, of the anchor from obstructions under which the flukes may be held, thereby preventing loss of the anchor which frequently occurs, when attempting to release fouled anchors of known construction by exerting excessive pull on the anchor.

An important object of the invention is to provide an anchor embodying a shank, and a spindle on which the flukes are pivotally mounted, means being provided for releasably securing the flukes in their extended positions, so that when the anchor is dropped, the flukes will be embedded in the bed of the body of water to anchor the boat with which the anchor is connected, in a predetermined position.

With the foregoing and other objects in view which will appear as the description proceeds, the invention consists of certain novel details of construction and combinations of parts, hereinafter more fully described and pointed out in the claim, it being understood that changes may be made in the construction and arrangement of parts without departing from the spirit of the invention as claimed.

Referring to the drawing

Figure 1 is an elevational view of an anchor constructed in accordance with the invention.

Figure 2 is a sectional view through the anchor spindle and fluke mounting.

Figure 3 is a sectional view through the spindle and fluke mounting, illustrating the spring tensioning means to regulate the action of the flukes and adapting the anchor for use under various conditions.

Referring to the drawing in detail, the anchor comprises the shank 5 which is formed with a hollow head 6 through which the fluke spindle 7 extends, the spindle 7 being secured within the hollow head, in any desired manner.

The flukes 8, are formed with bearing portions 9 which are secured to the hollow shaft 10 disposed between the bearing portions 9 and the spindle 7, the hollow shaft being formed with a cut-out portion 11 disposed at a point intermediate the ends thereof, the cut-out portion 11 falling opposite to the opening 12 formed in the hollow head 6.

Secured to the shank 5 of the anchor, is a leaf spring 13, which spring is formed with a curved end 14 presenting a lug 15 adapted to ride in the opening 12 and cut-out portion 11, the lug 15 being designed to engage the edges of the cut-out portion 11, to restrict rotary movement of the flukes with respect to the fluke spindle 7.

The spring 13 is provided with an opening to receive the securing bolt 16 which passes through an opening in the shank 5 of the anchor. The

2

spring 13 is further held in position by means of the plate 17 and adjusting plate 18, the plates 17 and 18 having openings adapted to align to receive the bolt 16. Thus, it will be seen that the adjustment of the plates 17 and 18, will tend to regulate the tension of the spring 13 so that the flukes may be adjusted for use in securing a boat under various conditions. That is to say, if the anchor is to be used in rough weather, to hold the boat, the tension on the spring would be increased, but under normal conditions, the tension of the spring would be adjusted so that the anchor would hold the boat against drifting, but the anchor would be released upon an excessive pull directed to the anchor.

Assuming that the flukes of the anchor are extended in a manner as shown by Figure 3 of the drawing, and the flukes are caught under a rock or lug. It is obvious that an excessive pull on the anchor, will cause the spring lug 15 to ride over the shoulder presented at one side of the cut-out portion of the hollow shaft, permitting the flukes to move to a position at such an angle with respect to the shank of the anchor, as to cause the flukes to ride from under the material holding the flukes against movement.

From the foregoing, it is believed that the construction and operation of the anchor forming the subject matter of this invention, will be clear, and that further detail disclosure as to the use and operation of the anchor is unnecessary.

What is claimed is:

In an anchor, a shank, a shaft mounted for rotary movement at one end of the shank, flukes secured to the shaft, a spring arm secured to the shank, one end of the arm being curved providing a lug adapted to engage the shaft, normally restricting movement of the shaft and flukes mounted thereon, a plate engaging the spring arm adapted to secure the spring arm to the shank, and means for adjusting the plate longitudinally of the shank towards and away from the lug, whereby the tension of the spring arm is regulated, regulating the movements of the shaft and flukes.
